REFRIGERATION

Albert R. Thomas, Evansville, Ind., assignor to
 Servel, Inc., New York, N. Y., a corporation of
 Delaware

Application August 13, 1936, Serial No. 95,792

25 Claims. (Cl. 236—99)

My invention relates to refrigeration, and more particularly to a control device for refrigeration apparatus.

It is an object of my invention to provide an improved control device which is simple and yet reliable in operation for controlling the heat supply of intermittent refrigeration apparatus.

Further objects and advantages of my invention will become apparent from the following 10 description and accompanying drawings forming a part of this specification, and of which Fig. 1 diagrammatically illustrates intermittent refrigeration apparatus provided with a control device embodying my invention; Fig. 2 is an enlarged vertical sectional view of the control device shown in Fig. 1; Figs. 3 and 4 are sectional views taken on lines 3—3 and 4—4, respectively, of Fig. 2; Fig. 5 is an enlarged vertical sectional view of a modification of the control device shown in Fig. 2; 20 and Figs. 6 and 7, and 8 are fragmentary sectional views taken on lines 6—6, 7—7, and 8—8, respectively, of Fig. 5 illustrating more clearly structural details of the control device.

Referring to Fig. 1, I have shown my improved 25 control device in connection with intermittent refrigeration apparatus of the type generally disclosed in Patent No. 2,027,057 to Carl Georg Munters. It is to be understood, however, that my invention can also be employed in connection 30 with other types of intermittent refrigeration apparatus. The refrigeration apparatus includes an absorption liquid reservoir 10, a generator 11, and a thermosiphon element 12 which is in the form of a coil disposed about the lower end of a flue 35 13 extending vertically upward through the generator. The generator 11 is heated by a gas burner 14 which projects a flame into the lower end of the flue 13 and to which a combustible gas is delivered from a source of supply through conduit 15, control device 16, and conduit 17.

The vessel 10, which is provided with fins 18 for 40 air cooling, holds the bulk of the absorption liquid of the apparatus which circulates between the vessel 10 and generator 11. A volume variation vessel 19 is connected by a conduit 20 with the vessel 10 and by conduits 21 and 22 with the upper part of the generator 11. The vessel 19 contains absorption liquid which is relatively stagnant during a vapor expulsion period and reduces to a minimum condensation of refrigerant vapor from the generator and absorption thereof during this period.

The generator 11 is connected with an evaporator 23 by means of conduit 22, a liquid column 45 trap including upper and lower vessels 24 and 25

connected by a conduit 26, and condensers 27 and 28 provided with cooling fins 29 and 30, respectively. To the upper part 31 of evaporator 23 is connected a lower header or a liquid containing part 32 which is in heat exchange relation with the upper condenser portion of a vaporization-condensation member 33, the lower vaporization portion of which is in heat exchange relation with the body or space to be refrigerated.

To the upper extended end of header 32 of 10 the evaporator 23 is connected a conduit 34 which communicates with a drain conduit 35. The conduit 35 is connected at its upper end with condenser 28 and has a part 36 in heat exchange relation with outer conduit 37 of heat exchanger 38 which is connected between the vessel 10 and generator 11. The conduit 35 is connected at its lower end to conduit 39 which extends between conduit 37 and volume variation vessel 19. A conduit 40 extending upwardly within vessel 25 20 communicates at its lower end with a conduit 41 which is connected to conduit 37 and volume variation vessel 19.

The refrigeration apparatus is charged with a 25 solution of refrigerant in an absorption liquid, such as, for example, a thirty per cent solution of ammonia and water. The system operates with alternate periods of absorption of refrigerant and expulsion of refrigerant vapor. During the vapor 30 expulsion period the burner 14 applies heat to generator 11 and coil 12 whereby strong absorption liquid flows from vessel 10 through conduit 42 and the heat exchanger 38 to coil 12. The heating of coil 12 causes a lifting of liquid and vapor through conduit 43 to the upper part of 35 generator 11. Due to the heating of generator 11, additional vapor is expelled from solution and the weak absorption liquid flows from generator 11 through conduit 44, 37, and 45 to the vessel 10.

The vapor conducted into the generator 11 40 through conduit 43 as well as the vapor expelled from solution in the generator flows through conduits 22, 26, and 46 into condenser 27 where most of it is liquefied. The vessel 19 may be insulated or somewhat heated to provide a stagnant 45 layer of liquid over the main body of absorption liquid so that a pool of concentrated solution is formed in communication with the generator through conduit 21 during the expulsion periods, which prevents substantial absorption of refrigerant vapor. No flow takes place through conduit 40 at this time. The liquid refrigerant in condenser 27, together with some gas, is forced upward through conduit 47 into the condenser 28, due to the pressure in the hot part of the system,

and in the latter any remaining vapor carried along with the liquid refrigerant is condensed. The condensed liquid refrigerant flows into the evaporator 23 and collects therein. The expulsion of refrigerant vapor continues until the evaporator contains so much liquid refrigerant that there is an overflow through conduits 34 and 35. When substantially pure refrigerant overflows through conduit 35 it becomes vaporized at part 36 which is in heat exchange relation with conduit 37. The entrance of vapor into conduit 39 causes an upward movement of warm liquid therein which is drawn from the liquid heat exchanger 38. The upward flow of warm liquid and gas in conduit 39 heats a thermal element or bulb 48 which is connected by tube 49 to the control device 16. When the bulb 48 becomes sufficiently heated the control device shuts off the supply of gas to the burner 14, as will be hereinafter explained.

When the supply of heat to the generator is stopped and the generator cools, liquid is drawn up into the trap conduit 26. The lower pressure in the generator, due to the absorption of vapor therein by absorption liquid, causes liquid in conduit 40 to recede until the latter is devoid of liquid, whereupon gas has free entry into conduit 41 from the evaporator 23. This sets up an upward flow of liquid in conduit 41 due to the entrance of gas therein from the evaporator 23. The liquid flows downward through vessels 19 and 10 and through conduits 45 and 37 back to conduit 41. The conduit 21 affords a direct communication between the absorption liquid and the generator 11 whereby the absorption of vapors above the liquid in the generator is accelerated.

The absorption period, which period is at a reduced pressure, has now started and refrigerant in evaporator 23 evaporates and takes up heat thereby producing cold. The cold produced in the evaporator 23 causes condensation and evaporation in the upper and lower portions of member 33, respectively, whereby heat is removed from and cold is produced in the body to be cooled.

A thermal element or bulb 50 is disposed within one end of the header 32 of the evaporator and is connected by a tube 51 to the control device 16. When the temperature of the evaporator increases to a predetermined value during the absorption period the thermal element 50 becomes sufficiently heated to operate the control device 16 and permit gas to be delivered to the burner 14 to start a heating period.

Referring to Fig. 2, the control device 16 includes a casing 52 having inlet and outlet openings 53 and 54 formed within bosses 55 and 56 to which are connected the conduits 15 and 17, respectively. The casing 52 adjacent the boss 56 is provided with an inwardly extending part 57 having a passage forming a part of the outlet 54. The projecting part 57 serves as a valve seat for a valve 58 which is carried at the outer free end of an arm or plate 59 which is secured at its other end to a resilient strip 60. The resilient strip 60 is fixed to an inwardly extending projection 61 of the casing 52. A leaf spring 62 is secured to the bottom of the projection 61 and the outer end thereof bears against the underside of the arm 59 to maintain the valve 58 in an open position.

The valve 58 controls the flow of gas to the burner 14 in response to the action of thermal elements 63 and 64 arranged at the upper and lower ends of the casing 52. The upper thermal

element 63 comprises an expansible diaphragm which is secured to and in open communication with a hollow hub member 65 to which is connected one end of the tube 49 which is connected at its other end to the bulb 48. The hub member 65 is mounted on a resilient diaphragm 66 which is secured at its peripheral edge between the upper end of the casing 52 and a cover plate 67 having an opening through which the tube 49 passes. The cover plate 67 is provided with an adjustment screw 68 for adjusting the position of the resilient diaphragm 66 and hence the position of the expansible diaphragm 63.

The lower thermal element 64 also comprises an expansible diaphragm which is secured to and in open communication with a hollow hub member 69 to which is connected one end of the tube 51 which is connected at its other end to the bulb 50. The hub member 69 is mounted on a resilient diaphragm 70 which is secured at its peripheral edge between the lower end of casing 52 and a cover plate 71 having an opening through which the tube 51 passes. The cover plate 71 is also provided with an adjustment screw 72 for adjusting the position of resilient diaphragm 70 and hence the position of expansible diaphragm 64.

The bulb 48, tube 49 and the expansible diaphragm 63, and the bulb 50, tube 51 and the expansible diaphragm 64 both constitute an expansible fluid thermostat adapted to contain a suitable volatile fluid which increases and decreases in volume with corresponding changes in temperature. The expansible diaphragms 63 and 64 expand and contract with an increase and decrease in volume of the volatile fluid, and these movements of the expansible diaphragms 63 and 64 are utilized to regulate valve 58 and control the flow of gas to the burner 14.

The movements of the expansible diaphragms 63 and 64 are transmitted to valve 58 by structure arranged in chamber 93 which is defined by the resilient diaphragms 66 and 70. The structure comprises a vertically disposed member 73 which extends through an opening 74 in the arm 59 and is provided with an enlarged head 75 at its upper end against which the expansible diaphragm 63 is adapted to bear. A greater part of the member 73 is recessed and forms a sleeve in which telescopically fits a second vertically disposed member 76 which is threadedly secured at its lower end to the expansible diaphragm 64. To the upper end of member 73 is secured a leaf spring 77 the outer end of which extends through an opening 78 in the member 73 and bears against the member 76 to provide a frictional engagement of the members 73 and 76. The leaf spring 77 is considerably stronger than the leaf spring 62 so that the latter is not effective to move the members 73 and 76 apart due to the frictional engagement therebetween. A stud 79 secured to the member 76 extends through a second opening in the member 73 and limits the extent of relative longitudinal movement between the members 73 and 76. To close the valve 58 when the member 73 is moved downward, a leaf spring 81 is provided which is secured at one end to the resilient strip 60. The outer end of leaf spring 81 is spaced from the arm 59 and provided with an opening through which the member 73 extends, the head 75 of the member 73 being adapted to bear against the leaf spring 81.

The operation of the control device 16 is as follows: Assuming that a heating or vapor ex-

pulsion period is in progress, the valve 58 and other parts of the control device 16 are substantially in the position shown in Fig. 2, and gas flows from conduit 15, inlet 53, chamber 93, outlet 54, and conduit 17 to the burner 14. During such heating period liquid refrigerant collects in the evaporator 23 until there is an overflow through conduits 34 and 35. When pure ammonia flows through conduit 35 it is vaporized at part 36, and the vaporized ammonia passes upwardly into conduit 39, as described above, to cause an upward flow of warm liquid and gas through the latter which heats the bulb 48. When the bulb 48 is heated to a temperature, such as 150° F., for example, the volatile fluid therein, which may be ether, is vaporized. This increase in volume of the volatile fluid causes expandable diaphragm 63 to expand whereby the member 73 against which it bears is moved downward. During this period the member 76 is stationary and the member 73 slides over the former against the frictional engagement which is effected by the leaf spring 71. With such downward movement of the member 73, the enlarged head 75 bears against the leaf spring 81 and flexes the arm 59 downward against the tension of leaf spring 62 to move valve 58 to its closed position and shut off the supply of gas to the burner 14.

When gas is no longer delivered to the burner 14 and heat is no longer applied to the refrigeration apparatus, the absorption period starts, as described above, and the evaporator 23 becomes cold. The cessation of heat supply to the refrigeration apparatus lowers the temperature of bulb 48 so that the volatile fluid becomes reduced in volume and the expandable diaphragm 63 contracts. The valve 58 remains in its closed position even after such contraction of the expandable diaphragm 63, due to the frictional engagement between the members 73 and 76 which is effected by the spring 71.

The cooling of evaporator 23 at the beginning of the absorption period causes the volatile fluid in bulb 50, tube 51, and expandable diaphragm 64 to become reduced in volume whereby the latter contracts and pulls member 76 downward against the frictional engagement effected by the leaf spring 71. The distance that members 73 and 76 are extended is limited by the stud 79 and opening 80 in the member 73.

After a lapse of time the ability of the refrigerant to evaporate is reduced and, due to supply of heat to the member 33 and evaporator 23, the temperature of the evaporator 23 rises. Upon a rise of the evaporator temperature to about 20° F., for example, the increase in volume of the volatile fluid in the expandable diaphragm 64 causes the latter to expand and move members 76 and 73 upward. This upward movement of both members 73 and 76 is due to the fact that the frictional engagement effected by spring 71 is not overcome. With such upward movement of member 73 the enlarged head 75 no longer bears against the leaf spring 81 and the leaf spring 62 becomes effective to move arm 59 upward whereby the valve 58 is moved to its open position. This permits gas to be supplied to the burner 14 to start a heating period of the refrigeration apparatus. A by-pass conduit 94 may be provided around the control device 16, as indicated in dotted lines in Fig. 1, to maintain a pilot flame during the absorption periods when the main supply of gas to the burner 14 is shut off.

In Figs. 5 to 7 I have illustrated a modification

of the control device shown in Fig. 2, with similar parts designated by the same reference numerals, the expansion and contraction of the expandable diaphragms 63 and 64 being utilized to control the valve 58 in the same manner as in the embodiment described above.

In this modification, the structure arranged in the chamber 93 for transmitting movements of the expandable diaphragms 63 and 64 to the valve 58 comprises an arm or plate 59', at one end of which is carried the valve 58. The opposite end of the plate 59' is secured to a resilient strip 60' which in turn is fixed to the inwardly extending projection 61' of the casing 52. The projection 61' is provided with an opening within which is a helical spring 62' adapted to bear against the underside of the plate 59' to maintain the valve 58 in its open position. A set screw 82 having a recess which receives the lower end of the spring 62' is threadedly secured to the bottom of the opening in the projection 61' for adjusting the tension of the spring 62'. The inwardly extending projection 57', which serves as a valve seat for the valve 58 and is provided with a passage forming a part of the outlet 54, is adapted to receive a cap screw 83. The cap screw 83 extends through an opening at the outer free end of the plate 59' and the enlarged head thereof limits the extent of upward movement of the plate 59' and the valve 58.

A vertically disposed member 73', which extends through an opening 74' in the plate 59', is recessed and forms a sleeve in which telescopically fits a second vertically disposed member 76' which is secured at its lower end to the expandable diaphragm 64. To the sleeve 73' at an opening therein is secured a short sleeve 84 which is internally threaded and receives a set screw 85, as shown in Fig. 6. The set screw 85 is recessed to receive one end of a helical spring 86, the opposite end of which fits over the reduced portion of a member 87. The member 87 is movable in an opening formed at the inner closed end of the sleeve 84 and bears against the member 76' in a splined portion 88 thereof to provide a frictional engagement of the members 73' and 76'. The frictional engagement provided between the members 73' and 76' is such that the spring 62' is not effective to move the members 73' and 76' apart. A stud 79 secured to the member 76' extends through a second opening 80' in the member 73' and limits the extent of relative longitudinal movement between the members 73' and 76'. To close the valve 58 when the member 73' is moved downward, a curved leaf spring 81' is provided which is secured at its inner end to the resilient strip 60'. The outer bifurcated arms of the spring 81' extend about the opposite side of the upper reduced portion of the member 73' and are in the path of movement of a pin 75' which is fixed to the member 73'.

In order that the valve 58 will close and open with a snap-action, I provide a weak permanent U-shaped magnet 89 which is mounted within the casing 52 about the projection 57', as clearly shown in Figs. 7 and 8. The magnet 89 is supported against the inner wall of the casing 52 by a yoke 90 which is mounted on the projection 57' by a cap screw 91. The plate 59' at its outer free end is substantially the same width as the magnet 89 and when it is moved downward adjacent to the upper ends of the magnet, the latter attracts the plate 59' to close the valve 58 with a snap-action. When the spring 62' tends to move the plate 59' upward and the force of 75

such upward movement exceeds the attractive force of the magnet, the plate 59' is moved upward and the valve 58 is snapped to its open position. The magnet 89 is provided with an opening 5 at the lower part thereof to receive a set screw 92. The set screw 92 bears against the underside of the projection 57' and is adjustable whereby the magnet 89 may be properly positioned with respect to the outer free end of the plate 59'.

10 The operation of the control device 16' is substantially the same as the operation of the control device 16 described above. During a heating or vapor expulsion period the bulb 48 eventually becomes heated with the result that the expansible 15 diaphragm 63 expands and moves the member 73' downward. During this period the member 76' is stationary and the member 73' slides over the former against the frictional engagement which is effected by the member 87. With such downward movement of the member 73', the pin 75' bears against the bifurcated arms of the leaf spring 81' and flexes the plate 59' downward against the tension of spring 62'. When the outer free end of the plate 59' is adjacent to the 20 upper ends of the magnet 89, the plate 59' is attracted toward the magnet and snaps the valve 58 to its closed position to shut off the supply of gas to the burner 14.

With the supply of gas to the burner 14 shut 30 off, the temperature of the bulb 48 is lowered with the result that the expansible diaphragm 63 contracts. The valve 58 remains in its closed position even after such contraction of the expansible diaphragm 63, due to the attraction of the plate 59' by the magnet 89 and the frictional engagement between the members 73' and 76'.

The absorption period starts with the cessation of heat supply to the refrigeration apparatus and, with the cooling of evaporator 23, the expansible diaphragm 64 contracts and pulls member 76' downward against the frictional engagement effected by the member 87. The distance that members 73' and 76' are extended is limited by the stud 79' and opening 80' in the member 73'. After a lapse of time the temperature of the evaporator 23 rises whereby the expansible diaphragm 64 expands and causes the members 76' and 73' to move upward due to the frictional engagement between these members. With such upward 50 movement of the member 73', pin 75' no longer bears against the leaf spring 81' and the spring 62' becomes effective to move the plate 59' upward against the attractive force of the magnet 89, whereby the valve 58 is snapped to its open 55 position. This permits gas to be supplied to the burner 14 to start a heating period of the refrigeration apparatus.

Although I have shown and described several embodiments of my invention, it will be apparent to those skilled in the art that modifications and changes may be made without departing from the spirit and scope of my invention, as pointed out in the following claims.

What is claimed is:

- 65 1. A control device for intermittent refrigeration apparatus including a valve for controlling the flow of fluid, structure for opening and closing said valve including a movable arm for carrying said valve, two members arranged telescopically one with the other, resilient means providing a frictional engagement between said members, a second resilient means biasing said arm to maintain said valve open, means operatively connecting said members and said arm whereby the latter is moved to close said valve

when one of said members is moved in one direction toward the other of said members, said second resilient means being rendered operative to open said valve when both of said members are moved in the opposite direction, and separate 5 thermal elements arranged to move one of said members in the one direction and both of said members in the opposite direction.

2. A control device for intermittent refrigeration apparatus including a valve for controlling 10 the flow of fluid, structure for opening and closing said valve including two members in frictional engagement and movable relative to each other, resilient means biasing said valve to an open position, means operatively connecting said members and said valve whereby the latter is closed against the tension of said resilient means when one of said members is moved in one direction relative to the other of said members, said resilient means being rendered operative to open 20 said valve when both of said members are moved in the opposite direction, and separate thermal elements arranged to move one of said members in the one direction and both of said members in the opposite direction. 25

3. A control device for intermittent refrigeration apparatus including a valve for controlling the flow of fluid, two members arranged telescopically one with the other and operatively connected to said valve, resilient means providing 30 a frictional engagement between said members, a second resilient means biasing said valve to an open position, a plurality of thermal elements arranged to act on said members, one of said elements being operative upon a predetermined 35 rise in temperature to move one of said members toward the other of said members to close said valve against the tension of said second resilient means, the frictional engagement between said members provided by said first resilient means 40 maintaining said valve closed upon a subsequent decrease in temperature when said one thermal element is no longer operative to close said valve, and the other of said thermal elements being operative upon a decrease in temperature to move 45 said members apart while said valve is closed and operative upon a subsequent predetermined rise in temperature to move both of said members whereby said second resilient means again becomes operative to open said valve. 50

4. A control device for intermittent refrigeration apparatus including a valve for controlling the flow of fluid, two members arranged telescopically one within the other, resilient means providing a frictional engagement between said 55 members, a second resilient means biasing said valve to an open position, means operatively connecting said members and said valve, a first thermal element arranged to act on said outer member, a second thermal element operatively connected to said inner member, said first element being operative upon a predetermined rise in temperature to move said outer member toward said inner member to close said valve against the tension of said second resilient means, the frictional engagement between said members provided by said first resilient means maintaining said valve closed upon a subsequent increase in temperature when said first thermal element is 60 no longer operative to close said valve, and said second thermal element being operative upon a decrease in temperature to move said inner member in one direction away from said outer member while said valve is closed and operative upon 65 70 75

- a subsequent predetermined rise in temperature to move both of said members in an opposite direction whereby said second resilient means becomes operative to open said valve.
5. A control device for intermittent refrigeration apparatus including a valve for controlling the flow of fluid, two members arranged telescopically one within the other and having limited longitudinal movement relative to each other, means operatively connecting said members and said valve, resilient means providing a frictional engagement between said members, a second resilient means tending to maintain said valve open, a first thermal element arranged to act on said outer member, a second thermal element operatively connected to said inner member, said first thermal element being operative upon a predetermined rise in temperature to move said outer member toward said inner member while the latter is stationary to close said valve against the tension of said second resilient means, the frictional engagement between said members provided by said first resilient means maintaining said valve closed upon a subsequent decrease in temperature when said first thermal element is no longer operative to close said valve, and said second thermal element being operative upon a decrease in temperature to move said inner member in one direction away from said outer member while said valve is closed and operative upon a subsequent predetermined rise in temperature to move both of said members in the opposite direction whereby said second resilient means again becomes operative to open said valve.
6. A control device for intermittent refrigeration apparatus including a casing having an inlet and outlet for fluid, a resilient diaphragm forming a gas-tight closure at each end of said casing, an expandible thermostat element located in each end of said casing and mounted on one of said diaphragms, a valve in said casing for controlling the flow of fluid, two members disposed between said thermal elements and arranged telescopically one within the other, means operatively connecting said members and said valve, resilient means providing a frictional engagement between said members, a second resilient means tending to maintain said valve open, one of said elements being arranged to act on said outer member and the other of said elements being operatively connected to said inner member, said first element being operative upon a predetermined rise in temperature to move said outer member toward said inner member to close said valve against the tension of said second resilient means, the frictional engagement between said members provided by said first resilient means maintaining said valve closed upon a subsequent decrease in temperature when said first element is no longer operative to close said valve, and said second thermal element being operative upon a decrease in temperature to move said inner member away from said outer member while said valve is closed and operative upon a subsequent predetermined rise in temperature to move both of said members toward said first element whereby said second resilient means again becomes operative to open said valve.
7. A control device for intermittent absorption refrigeration apparatus including a casing having an inlet and outlet for fluid, two expandible thermal elements located substantially in line with each other within said casing, a valve in said casing for controlling the flow of fluid, structure including two members in frictional engagement and movable relative to each other and so constructed and arranged between said thermal elements that one of said elements is operative to move one of said members to close said valve upon a predetermined rise in temperature and the other of said elements, due to said frictional engagement, is operative to move both of said members to open said valve upon a predetermined rise in temperature.
8. A control device for intermittent refrigeration apparatus including a casing having an inlet and outlet for fluid, two expandible thermal elements located substantially in line with each other within said casing, a valve for controlling the flow of fluid, two members arranged telescopically one within the other, resilient means providing a frictional engagement between said members, a second resilient means biasing said valve to an open position, means operatively connecting said members and said valve, one of said thermal elements being arranged to act on said outer member and the other of said thermal elements being operatively connected to said inner member, said first thermal element being operative upon a predetermined rise in temperature to move said outer member toward said inner member while the latter is stationary to close said valve against the tension of said second resilient means, the frictional engagement between said members provided by said first resilient means maintaining said valve closed upon a subsequent decrease in temperature when said first thermal element is no longer operative to close said valve, and said second thermal element being operative upon a decrease in temperature to move said inner member away from said outer member while said valve is closed and operative upon a subsequent predetermined rise in temperature to move both of said members toward said first thermal element whereby said second resilient means becomes operative to open said valve.
9. A control device for intermittent refrigeration apparatus including a valve for controlling the flow of fluid, structure for opening and closing said valve including a movable arm for carrying said valve, a magnet arranged in the path of movement of said arm adapted to be contacted by the latter, two members arranged telescopically one within the other, resilient means providing a frictional engagement between said members, a second resilient means biasing said arm to maintain said valve open, means operatively connecting said members and said arm whereby the latter is moved adjacent to said magnet and attracted thereby to close said valve when one of said members is moved in one direction toward the other of said members, said second resilient means being operative to move said arm away from said magnet against the attractive force of the latter to open said valve when both of said members are moved in the opposite direction, and separate thermal elements arranged to move one of said members in the one direction and both of said members in the opposite direction.
10. A control device for intermittent absorption refrigeration apparatus including a casing having an inlet and an outlet for fluid, two expandible thermal elements located substantially in line with each other within said casing, a movable arm and a valve carried thereby arranged within said casing for controlling the flow of fluid, structure including two members in frictional engagement and movable relative to each other and so constructed and arranged between said thermal elements that one of said elements is operative to move one of said members to close said valve upon a predetermined rise in temperature and the other of said elements, due to said frictional engagement, is operative to move both of said members to open said valve upon a predetermined rise in temperature.

each other and so constructed and arranged that one of said elements is operative to move one of said members to effect movement of said arm to close said valve upon a predetermined rise 5 in temperature, and the other of said elements due to said frictional engagement is operative to move both of said members to permit an opposite movement of said arm to open said valve upon a predetermined rise in temperature, and 10 a magnet arranged within said casing in the path of movement of said arm whereby said valve is closed and opened with a snap-action.

11. For use with refrigeration apparatus, a control device, and means for operating said device including two members in frictional engagement with each other, one of said members being operatively connected to said control device, and means for moving said members responsive to conditions at different places in the 15 refrigeration apparatus respectively, movement of both of said members responsive to the condition at one place in the refrigeration apparatus being due to said frictional engagement.

12. For use with refrigeration apparatus, a 20 control device, and means for operating said device responsive to conditions in two different parts of the refrigeration apparatus including a first thermostat arranged to operate said device in one direction only, and a second thermostat 25 connected in frictional engagement with said device so as to effect operation thereof due to said frictional engagement.

13. A control device and operating means as set forth in claim 11 in which said two frictionally engaged members are in telescopic relation.

14. A control device and operating means therefor as set forth in claim 12 in which the control device is a valve for controlling flow of 40 fuel to a heater.

15. For use with refrigeration apparatus, a control device including a valve, a magnetic member for imparting snap action to the opening and closing of said valve, a first thermostat 45 arranged to cause operation of said valve in one direction only, and a second thermostat connected to said valve by frictional engagement so as to effect operation of said valve due to said frictional engagement.

50 16. For use with intermittent absorption refrigeration apparatus, a control device including a valve for controlling flow of fuel to a heater for the refrigeration apparatus, two members in frictional engagement with each other, one of 55 said members being operatively connected to said valve, a first thermostat for moving said first member in one direction only, and a second thermostat operatively connected to the other of said members so that said second thermostat 60 operates said valve through said members due to said frictional engagement.

17. In an intermittent absorption refrigeration apparatus, a generator, a heater for said generator, a cooling element, a device for controlling said heater, and means for operating said device including a first thermostat for operating said device in one direction only to shut 65 down said heater responsive to increase in temperature of said generator, and a second thermostat connected by frictional engagement with said device so as to effect operation thereof responsive to temperature of said cooling element only when said frictional engagement is not overcome and thereby maintaining said heater in 70 its shut down condition when the temperature of 75

said cooling element is relatively low and causing said heater to start upon increase in temperature of said cooling element.

18. The combination in a refrigeration apparatus as set forth in claim 17 in which said heater is a fluid fuel burner and said control device is a valve for controlling flow of fuel to the burner.

19. For use with refrigeration apparatus, a control member, two elements operatively associated with said control member and movable relative to each other, means providing frictional engagement between said elements, means responsive to changes in a first condition of the refrigeration apparatus and acting on one of 15 said elements for causing movement thereof to move said control member to a first position, and means responsive to changes in a second condition of the refrigeration apparatus and acting on the other of said elements to first overcome 20 said frictional engagement and cause relative movement of said members while said control member is in said first position, and, with further changes in said second condition, subsequently causing movement of both of said elements, due to said frictional engagement, to move said control member from said first position to a second position.

20. For use with refrigeration apparatus, a control member, structure for operating said 30 control member including two elements in frictional engagement and movable relative to each other, means responsive to a condition of the refrigeration apparatus whereby one of said elements overcomes the frictional engagement and 35 moves relative to the other to effect movement of said control member to a first position, and means responsive to a condition of the refrigeration apparatus whereby both of said elements move, due to the frictional engagement therebetween, to effect movement of said control member from the first position to a second position.

40 21. A control device for refrigeration apparatus including a valve for controlling flow of 45 fluid fuel, a plurality of elements operatively associated with said valve, means providing a frictional engagement between said elements; means responsive to a condition of the refrigeration apparatus and acting on one of said elements to close said valve, means responsive to a condition of the refrigeration apparatus and acting on the other of said elements to open said valve, the frictional engagement provided by said first-mentioned means permitting relative 55 movement between said elements while said valve is closed and preventing such relative movement when said last-mentioned means acts on the other of said members to open said valve.

50 22. In a control device for refrigeration apparatus including a control member movable between first and second positions and two co-operating elements for operating said control member in response to different conditions in the refrigeration apparatus, the improvement 60 which consists in providing frictional engagement between said elements which permits relative movement of said elements while said control member is in the first position and prevents such relative movement whereby movement 65 of said control member may be effected from the first position to the second position.

70 23. A control device for refrigeration apparatus including a valve for controlling flow of fluid fuel, two thermal elements, and structure op- 75

eratively associating said valve and said thermal elements and including two members in frictional engagement, and movable relative to each other, said structure being so constructed and arranged that one of said elements is operative to move one of said members to close said valve upon a predetermined rise in temperature and the other of said elements is operative to move both of said members, due to the frictional engagement therebetween, to open said valve upon a predetermined rise in temperature.

24. Apparatus for controlling an absorption refrigeration system including a control element mechanism for operating said control element including two members in frictional engagement

and movable relative to each other, means responsive to a temperature condition to cause one of said members to move said control element to a first position, means responsive to a different temperature condition to cause both of said members, due to the frictional engagement therebetween, to move said control element from the first position to a second position, and means cooperating with said control element to cause the latter to move with a snap-action.

25. Apparatus as set forth in claim 24, in which said means to cause said control element to move with a snap-action includes a magnetic member.
